PHOTOGRAPHIC FOAM PROCESSING

Leonard W. Tregillus, Rochester, N. Y., assignor to Eastman Kodak Company, Rochester, N. Y., a corporation of New Jersey.

Application August 26, 1953, Serial No. 376,733

3 Claims. (Cl. 96—61)

This invention relates to photographic processes and particularly to a method for processing photographic layers.

In specialized applications of photography employing photosensitive emulsions it is desirable to apply to the emulsion layer or to any surface associated with the photographic process a minimum amount of solution required to develop, stabilize, tone, dye or otherwise react with the photosensitive material or its reaction products in the emulsion layer. Various methods have been proposed for spreading photographic solutions by means of brushes, sponges or bead applicators. In each case there is the danger of spilling the bulk fluid or applying too much or too little fluid to the photographic sheet. In many cases, the photographic sheet is simply immersed in the solution to avoid the complications of these fluid spreading means but this has the disadvantage with absorbing materials of undesirably wetting the base or support for the photosensitive layer.

It is therefore an object of the present invention to provide a novel method for processing photographic layers. A further object is to provide a processing method which does not involve excess wetting of the photographic support. A still further object is to provide a processing method applicable to photographic transfer processes. Other objects will appear from the following description of my invention.

These objects are accomplished, in the broader aspects of my invention, by spreading the processing agent on the photographic sheet as a foam.

In the accompanying drawing Fig. 1 is a perspective view showing a method of applying the foam to a spreading device.

Fig. 2 is a sectional view showing the manner in which the spreading device applies the foam to a photosensitive sheet, and

Fig. 3 is a sectional view showing a method of transfer of a foam-developed photographic image to a second sheet.

Foam as used herein means a system consisting of a concentrated dispersion of gas bubbles in a liquid. The gas bubbles may be macroscopic, microscopic or ultra-microscopic, whereas the layers of liquid which separate them are of micronic or submicronic dimensions (10μ to $5\text{ m}\mu$). A foam may therefore be considered as a system of laminae which enclose gas bubbles in the interstices (see Thorpe's Dictionary of Applied Chemistry, J. F. Thorpe and M. A. Whitely, Longmans, Green and Company, London, 1941). In the foam used for photographic processing according to my invention, the volume of liquid is preferably between 2% and 30% of the foam volume.

The novel feature of my invention is the foam processing of the photographic sheet. The physical structure and stability of the foam may be varied within wide limits to meet the requirements of the particular process and application for which it is intended. By suitable choice

2

of foaming agents, it is possible to produce foams consisting of large or small bubbles carrying a minimum or maximum of liquid and having a stability from less than a second to several hours or days. With a foam of short life, for example, 3 seconds, it is possible to spread the foam over the photosensitive sheet and the bubbles break down almost immediately to leave a uniform layer of liquid on the sheet. On the other hand a stable foam requires some mechanical means of moving the bubbles on the sheet to insure uniformity of reaction and wetting and also some means either physical or chemical of removing or dispersing the bubbles after the reaction is complete. With an unstable foam it is generally necessary to provide traps to collect the excess liquid from the collapsed bubbles and baffles to prevent splatter from reaching parts of the apparatus which are intended to be kept dry. A stable foam may be more easily contained within the reaction areas but a trap should be provided for reconverting the excess foam back into a liquid or otherwise disposing of it. It is to be understood that my invention includes the use of foams of any degree of stability which may be used to apply a processing agent to a photographic sheet.

The production of foams requires that the parent liquid must possess certain physical properties such as low surface tension, a high spreading coefficient, low volatility, etc. A foaming agent, generally surface-active, is usually added to the solution to produce a foam of the required stability. Solutions for photographic processing in most cases contain fairly high concentrations of electrolytes some of which may have foaming or anti-foaming properties. The type of foaming agent to be added is, therefore, dependent on the composition of the solution and its pH. Foams of short life may be produced from certain developing solutions by the addition of lower alkyl alcohols, e. g., isopropyl alcohol, n-butyl alcohol, tertiary butyl alcohol and isoamyl alcohol. In acid stabilizing baths short life foams may be produced by the acid itself, e. g., acetic acid.

For longer-lived foams, a more highly surface-active agent is required. Cationic detergents, e. g., Aerosol IB (diisobutyl sodium sulfosuccinate), may be used for solutions of low pH and anionic detergents, e. g., Duponol ME (sodium lauryl sulfate) for solutions of high pH. Examples of foam-producing non-ionic surface-active agents are saponin and Onyxol 9162 (a condensed fatty acid alkanolamide), which may be used in acid or alkaline solutions. The choice of a foaming agent depends on the specific composition of the solution. In an acid stabilization bath, for example, a short-lived foam is obtained due to the presence of acetic acid. The addition of 0.1% Aerosol IB gives a more stable foam if the photographic stabilizing agent is thiourea, but not if the stabilizing agent is sodium thiosulfate. Combinations of foaming and anti-foaming agents may be used to obtain the desired foam life and bubble size. Certain addenda such as glycerine are useful in producing flexible bubble walls. It is the purpose of my invention to use foam for photographic processing regardless of the particular agent used to produce the foam.

The instability of most foams necessitates that they be generated immediately before use. In the case of developing solutions, continued exposure of the thin films of liquid in the foam to the air would lead to premature oxidation, evaporation and drainage. The foams are produced by introducing a gas into the liquid or generating a gas within the liquid, for example, by the release of pressure, to form a continuum of bubbles. The former method has been most easily accomplished in the laboratory by blowing air into the stem of a small Pyrex Büchner funnel which has a fritted glass disc. With a small amount

of solution poured into the funnel and the air turned on the foam is collected at the top of the funnel. A photographic sheet, emulsion side down, is passed over the top of the funnel to come in contact with the foam. The short time during which the air is in contact with the foam bubbles does not lead to appreciable oxidation in the case of developing solutions. In the case where the gas is stored under pressure with the solution in an enclosed container a gas compatible with the solution components should be chosen. Dichlorodifluoromethane is satisfactory providing that an agent is present to increase its solubility in water when under pressure. In some cases the surface-active agent performs this function.

A particular advantage of the foam processing system is that the means for supplying the foam may be a disposable completely self-contained unit. Apparatus of this type is in use commercially for dispensing whipped cream and shaving lather. In a photographic processing system the foam making cans containing the appropriate solutions may be attached to the processing apparatus to supply foam as required, thus eliminating the need for trays or complicated liquid spreading means.

In addition to providing a foam for photographic processing, it is contemplated by my invention that in the later stages of the operation reconversion of the foam to liquid may be accomplished. For example, the bulk of the excess foam is greatly reduced if reconverted to a liquid in which state it can be caught in small traps. It is to be preferred but not entirely necessary that the foam attached to the photographic sheet become a liquid in order to achieve more uniform spreading.

De-foaming may be brought about by physical or chemical means. The suction of the capillary action of blotting paper will cause a foam to collapse with great rapidity, particularly if the normal life of the foam is less than one minute. At the same time, the blotting paper serves as an efficient trap for the excess liquid from the foam. The removal of a stable foam from the surface of the photographic sheet may be accomplished by the application of a squeegee or doctor blade, or passage of the sheet between a pair of wringer rollers. The collapsing of the foam by chemical means may be brought about by suitable choice of a foaming agent so that the life of the foam is just sufficient to transport the liquid from the foam generator to the surface of the photo-sensitive sheet. It is possible also to incorporate in the surface at which de-foaming is to take place certain anti-foaming agents which will react with the foaming agent in the foam. As an example, a piece of blotting paper which has been soaked in 10% potassium chloride solution and dried will cause a quicker collapse of the foam than untreated blotting paper, if the foaming agent is Duponol ME, the potassium salt of which is insoluble.

Apparatus for foam processing must provide principally a means of applying the foam to the photosensitive surface. For laboratory purposes the photographic sheet, emulsion side down, was moved over the top of the Büchner funnel with fritted glass disc, from which the foam was issuing. After allowing a few seconds for development to take place the sheet was squeegeed. If a stable foam is used the problem of containment of the foam is simplified in that there is a minimum tendency for the foam to run. The photosensitive sheet may constitute the top, bottom or side of the space in which the foam is released. Instead of a squeegee, a wringer roller may be employed to remove the excess liquid or foam. Since only one side of the photosensitive sheet is wet and only for a short time the sheet is substantially dry after passage through the wringer.

An elementary system for developing and processing a sheet of silver halide photosensitive paper with a stable foam is shown in Figures 1 and 2 of the accompanying drawing. As shown therein, a spreading device, consisting of a doctor blade 10 set at an acute angle and two side members 11, serving to hold the doctor blade 10 at its predetermined angle, is first sprayed as in Figure 1, while in

an inverted position, with foam from a pressurized container 12. The spreading device, in an upright position, is set down, as in Figure 2, on a sheet 13 having thereon an exposed photosensitive layer 14, sheet 13 resting on a sheet of blotting paper 15 for the purpose of absorbing excess foam. On setting the spreading device down on the photosensitive sheet 13, the doctor blade 10 presses the foam laterally over the photosensitive layer 14 to the limits established by the side members 11. The spreading device is moved over the photosensitive layer 14, with the edge of the doctor blade 10 going last and removing substantially all of the excess surface foam 16. The acute angle at which the doctor blade 10 is set serves to slide the foam 16 over the photosensitive surface 14 to insure uniform development. The energy of the developing agents in the foam and the size and speed of movement of the spreading device are adjusted so that development of the image 17 is essentially complete while the photosensitive layer 14 is under the doctor blade 10. After the foam is spread on the photosensitive layer 14, the sheet 13 is inverted and blotted on sheet 15 to remove any foam which may have slipped out from under the spreading device. A second foam containing stabilizing agent is dispensed on a second spreading device from a second pressurized can and the spreading and blotting process is repeated. This completes the processing.

Application of a foam in photographic processing is ideally suited to the so-called solvent transfer process where development and transfer are effected by only one bath. A process of this type is described in Rott U. S. Patent 2,352,014, June 20, 1944. When processing a material of this type a pair of wringer rollers may be arranged so that the negative sheet and the receiving sheet can be fed face-to-face between them, one or both of the sheets having come previously in contact with the foam-containing processing agents.

Foam processing is also especially suited to the method described in Yutzy and Yackel U. S. Patent 2,740,717, in which the negative developer is contained within the negative emulsion and is non-wandering and the receiving sheet contains compounds which precipitate the silver complex ions diffusing from the negative sheet without the aid of a developing agent, thereby eliminating the problem of receiving sheet stain.

The method of processing a material of the solvent transfer type is illustrated by the sectional view of Fig. 3. As shown therein, a sheet of paper or other suitable flexible support 18 has thereon a silver halide emulsion layer 19 which may or may not contain a developing agent. This layer is exposed in the usual way and a foam of processing agent 20 is then applied to it and spread over the photosensitive surface in any suitable manner. The sheet carrying the foam is then placed in contact with a receiving sheet 21 and the sandwich is passed between wringer rollers 22 which press the two sheets together. After remaining in contact for about a minute the sheets are stripped apart and a positive image is found on the transfer sheet 21.

As illustrated in Fig. 3, it is necessary in some systems that the receiving sheet 21 be water-proof in order that the sandwich does not become too dry during the course of the transfer operation owing to the absorption of liquid by the paper base of sheet 21. If receiving sheet 21 is, for example, baryta paper and not water-proofed, then application of a foam of processing agent 20 to both sheets 18 and 21 will supply enough moisture for the transfer operation.

In addition to the applications referred to above the technique of foam processing is useful in many other systems; for example, a foam processing agent may be applied to a sensitive material described in Yutzy and Yackel U. S. Patent 2,596,756, May 13, 1952, in which unhardened portions of gelatin are transferred from a sensitive layer to a receiving sheet in a document copying process. A further use of foam processing is in aerial proto-reconnaissance, where it is desirable to process ordinary films

before the aircraft has returned to its base. Rapid processing of motion picture films for television may be speeded up with reduction in the amount of apparatus required because of the minimum amount of solution applied to the film and the consequent reduction in swelling of gelatin. In the processing of duplitzed motion picture film a foam can be used easily to apply solution to only one side of the film at a time. Foam solutions may be compounded to develop, bleach, dye, tone or clear the film as required. Similarly, foam application to a multilayer color film may be employed to restrain reaction to the outermost layer where desired. Facsimile reproduction can be simplified with foam processing.

Foam processing techniques may be used with photographic processes other than those based on silver halide sensitivity. Reproduction processes employing diazonium compounds may be simplified by applying the coupling solutions as a foam. Development by foam may be applied also to systems based on the photosensitivity of iron salts.

Examples of foam processing follow, it being understood that these are merely illustrative and that the invention is not limited to the materials, proportions, apparatus or manipulations set forth therein.

Example 1

A sheet of thin coated gelatino-silver chloride paper was exposed to a line image and was then drawn over the top of a foam generator, the foam being produced from 10 cc. of developing solution in a 50 cc. funnel with a fritted glass plate, air being supplied through the stem by means of a hose connected to an air compressor, with a needle valve control. In order to make up the final developing solution, a developing solution was first made up as follows:

	Grams
N-methyl-p-aminophenol sulfate	3.1
Hydroquinone	12
Sodium sulfite, desiccated	45
Sodium carbonate, monohydrate	80
Potassium bromide	1.9
Water to 1 liter.	

To 10 cc. of this developing solution there were added from 0.001 to 0.01 g. of Duponol ME (sodium lauryl sulfate) and 0.2 cc. of isopropyl alcohol. After placing this solution in the apparatus and turning on the air the exposed paper was moved across the top of the funnel in contact with the foam. After allowing 5 seconds for development the excess developer on the face of the paper was removed with a squeegee. The sheet was then moved over the top of a second funnel in contact with the foam from the following stabilizing solution:

Thiourea 10% solution	cc	10
Acetic acid	cc	0.5
Saponin	g	0.0004

After 10 seconds the excess solution was removed with a squeegee. The image area had good black tones and the non-image areas were resistant to print-out upon exposure to a No. 2 Photoflood lamp for one minute at two inches.

Example 2

A sheet of thin-coated gelatino-silver chloride paper was exposed to a line image and processed with a developer and a stabilizer in the manner illustrated by Figures 1 and 2. In order to make up the final developing solution, a developing solution was first made up as follows:

Water	cc	200
Sodium sulfite, desiccated	grams	10
Hydroquinone	do	4
Sodium hydroxide	do	3.2
Potassium bromide	do	0.4
1-phenyl-3-pyrazolidone	do	0.4
Onyx-ol 9162 (condensed fatty acid alkanol-amide)	cc	8.0

To 50 cc. of this developing solution, in the pressurized container chilled in a Dry Ice-acetone bath, there was added 10 cc. of liquid dichlorodifluoromethane; after capping, the container was warmed to room temperature for use.

In a similar manner, a stabilizing solution was prepared as follows:

Water	cc	90
Thiourea	grams	10
Acetic acid	cc	15
Onyxol 9162	cc	2

A second pressurized container was filled with 50 cc. of this solution and 6 cc. of liquid dichlorodifluoromethane.

The foam of the developing solution was dispensed on the spreading device from which it was transferred to the photosensitive paper. After blotting, the photosensitive paper had applied to it a foam of the stabilizing solution in a similar manner.

Example 4

This example illustrates foam processing in a solvent transfer process.

A receiving sheet was first prepared in a manner similar to that disclosed by E. H. Land in U. S. Patent No. 2,635,048 by rubbing baryta paper with a mixture consisting of:

Silica (Linde)	grams	30
1% sodium sulfide	cc	280
Cadmium acetate	grams	3
1% lead acetate	cc	1
Water	cc	20

The sheet was squeegeed and dried before use.

A negative-speed gelatino-silver bromoiodide emulsion was exposed to a continuous tone image and was developed by foam application in the manner described in Example 1 with a developer consisting of:

40 Hydroquinone	gram	0.35
Sodium sulfite, desiccated	do	0.89
Sodium thiosulfate	do	0.15
Sodium hydroxide	do	0.28
Potassium bromide	do	0.025
Benzotriazole 0.5% solution	cc	0.25
Isopropyl alcohol	cc	0.1
Water	cc	10

Immediately afterwards the foam was applied to the receiving sheet. The negative sheet and the receiving sheet were placed in contact face-to-face and passed between a pair of rollers. After one minute the sheets were separated and a positive image of good characteristics was obtained on the receiving sheet.

It will be understood that the examples and modifications described herein are illustrative only, and that my invention is to be taken as limited only by the scope of the appended claims.

What I claim is:

1. The method of forming a visible image in an exposed gelatino-silver halide emulsion layer, which comprises spreading on said exposed layer a foam consisting of a concentrated dispersion of gas bubbles in a liquid the volume of liquid being between 2% and 30% of the foam volume, said foam containing an aqueous solution of an anionic surface-active agent and at least hydroquinone as a developing agent, allowing said foam to remain in contact with said layer for about 5 seconds, removing the excess foam from said layer, spreading on said layer a stabilizing foam of thiourea and a surface-active agent which creates a stable physical foam for an appreciable period of time, allowing said stabilizing foam to remain in contact with said layer for about 10 seconds, and then removing the excess stabilizing foam from said layer.
2. The method of forming a visible image in an exposed gelatino-silver halide emulsion layer, which com-

prises spreading on said exposed layer a foam consisting of a concentrated dispersion of gas bubbles in a liquid, the volume of liquid being between 2% and 30% of the foam volume, said foam containing an aqueous solution of approximately 1.2%, hydroquinone, approximately .3%, N-methyl-p-aminophenol sulfate, approximately 4.5%, sodium sulfite and .01 to .1% sodium lauryl sulfate, allowing said foam to remain in contact with said layer for about 5 seconds, removing the excess foam from said layer, spreading on said layer a stabilizing foam comprising an aqueous solution of thiourea, acetic acid and saponin, allowing said stabilizing foam to remain in contact with said layer for about 10 seconds, and then removing the excess stabilizing foam from said layer.

3. The method of stabilizing an exposed and developed silver halide emulsion layer which comprises treating said exposed and developed layer with a foam consisting of a concentrated dispersion of gas bubbles in a liquid, the volume of liquid being between 2% and 30% of the foam

volume, said foam containing thiourea and a surface-active agent which creates a stable physical foam for an appreciable period of time.
